UNITED STATES PATENT OFFICE.

EDWIN R. SMITH, WILLIAM R. RICE, AND JOHN R. JACKSON, OF FITCHBURG, MASSACHUSETTS, ASSIGNEES TO AUTO-MAILING MACHINERY COMPANY, A CORPORATION OF MASSACHUSETTS.

ADDRESSING MACHINE.

Application filed November 4, 1922. Serial No. 599,122.

This invention relates to a machine for addressing envelopes and other similar articles from previously prepared stencils.

It is the object of our invention to improve the construction and operations of such machines and to render them more reliable and efficient when in use.

With this general object in view, one feature of our invention relates to the provision of improved devices for feeding the stencils, including means for counting the stencils actually fed and for preventing damage in the event of a misplaced or blocked stencil. We have also provided new and improved mechanism for feeding the envelopes singly to the conveying devices and for stopping and releasing the envelopes at the printing point.

A further detail of our invention pertains to a presser or platen, removably mounted to permit inspection of parts disposed thereunder.

Our invention further relates to arrangements and combinations of parts which will be hereinafter described and more particularly pointed out in the appended claims.

A preferred form of our invention is shown in the drawings in which

Fig. 1 is a plan view of our improved machine;

Fig. 2 is a detail side elevation, looking in the direction of the arrow 2 in Fig. 1;

Fig. 3 is a sectional side elevation, taken along the line 3-3 in Fig. 1;

Fig. 4 is a detail sectional side elevation, taken along the line 4-4 in Fig. 1;

Fig. 5 is a partial front elevation, looking in the direction of the arrow 5 in Fig. 1;

Fig. 6 is a plan view of parts of the feeding mechanism, taken along the line 6-6 in Fig. 3;

Fig. 7 is a plan view of parts of the driving and conveying mechanism, looking in the direction of the arrow 7 in Fig. 8;

Fig. 8 is a side elevation of the driving mechanism shown in Fig. 7;

Fig. 9 is a rear elevation of the machine with certain parts omitted, looking in the direction of the arrow 9 in Fig. 1; and

Fig. 10 is a detail elevation of parts of the stencil feed.

Referring to the drawings, we have shown a machine particularly adapted for addressing envelopes. The several parts of

the machine are assembled upon a frame 55 comprising a base or table 20 and end frame members 21 and 22. A main driving shaft 23 (Fig. 5) is supported in fixed bearings 26 and 27 and is provided with a pulley 28 connected by a belt 29 to a smaller pulley 30 on a countershaft rotatable in a fixed bearing 31. A gear 32 and a pinion 33 form a driving connection to the countershaft from a motor 34, thus providing means by which the main shaft 23 may be continuously rotated. It will be understood that the driving mechanism shown is illustrative only and that any other suitable driving connections may be substituted therefor.

The driving shaft 23 is connected by bevel gears 35 and 36 (Figs. 3 and 5) to a cross shaft 37 (Fig. 3). The shaft 37 rotates in bearings 38 depending from the table 20 and is provided at its rear end with a wide face pulley 39 connected by a cross belt or rope 40 to a pulley 41 at the end of the ink fountain 42. The pulley 41 is connected to drive a mixing device in the ink fountain.

A box or casing 43 is mounted above the ink fountain 42 and contains ink rollers (not shown) actuated from the shaft 37 to convey ink to the stencils of the addressing machine. This inking mechanism, however, forms no part of our present invention and it is merely necessary to state that the rollers intermittently receive a fresh supply of ink from the ink fountain and transfer the ink through the stencils to the envelopes or other articles to be addressed.

The driving shaft 23 is connected through a sprocket 45, a chain 46 (Fig. 8) and a sprocket 47 to a feed shaft 48. The shaft 48 is thus driven continuously and rotates feeding rolls 49 (Fig. 6) which are each provided with pads 50 of rubber or other friction material extending over a portion only of the periphery thereof.

The rolls 49 are located adjacent the lower end of an inclined feed box or chute 100 comprising a bottom 51 (Fig. 3), sides 52 and a curved top and end plate 53. The envelopes E placed in the feed box descend by gravity to the position indicated in Fig. 3, at which point the lowest envelope is advanced between the roll 49 and the curved end of the plate 51, where it is engaged by the friction pads 50. A series of retarding

rolls 54 are mounted on a shaft 55 above and closely adjacent the rolls 49. The shaft 55 is positively driven from the shaft 48 by a chain 56 and sprockets 57 and 58 (Figs. 7 and 8). The adjacent surfaces of the rolls 49 and 54 thus move oppositely and the upper rolls 54 act to brush back or retard any extra envelope advanced by the feed rolls 49.

10 In order to assist the advance movement of the lower envelopes toward the feed rolls, we have provided an agitating device comprising a pad or block 60 (Fig. 3) mounted on an arm 61 pivoted at 62 and intermittently engaged by a cam 63 (Fig. 6) on the feed shaft 48. The block 60 thus repeatedly engages the envelopes in the feed box, forcing them slightly backward and then releasing them so that the lowermost envelope may 15 be easily advanced by gravity to the feed rolls.

As each envelope is delivered singly by the rolls 49, it is received between conveyor belts 64 and 65 (Fig. 3). The upper belts 25 64 are supported on driving pulleys 66 and guide rolls 67. The pulleys 66 are fixed to a cross shaft 68 which is connected by a pinion 69 and gear 70 (Fig. 8) to the feed shaft 48. The lower belts 65 are mounted 30 on guide rolls 71 and driving pulleys 72, the latter being fast on a cross shaft 73. The shaft 73 is connected by a pinion 74 to a pinion 75 (Fig. 7) on the upper conveyor shaft 68. By these connections, the upper 35 and lower belts are continuously driven at the same speed.

As the belts 64 and 65 are moved continuously, it is necessary that a stop be provided to hold the envelopes momentarily stationary while the address is placed thereon. For this purpose, we have provided stop pins 80, (Fig. 3) vertically slidable in fixed bearings 81 and connected at their upper ends to arms 82 on a rock shaft 83. An arm 45 84 on the shaft 83 is connected by a link 85 to a slotted plate 86 (Fig. 4) through which extends the feed shaft 48. A cam 87 on the shaft 48 intermittently engages a cam roll 88 on the plate 86 and thus raises the 50 stop pins to permit an envelope to pass thereunder. A spring 89 (Fig. 4) normally retains the stops in operative position.

As the ink rollers press the stencils against the envelope to be addressed, a presser foot or platen (Fig. 3) is depressed to engage the upper face of the envelope. The platen is adjustably secured by clamps 91 to the lower end of a plunger 92 slidably mounted in a bracket 93 secured to the vertical face of a frame member 94 by a stud 95 and clamping nut or handle 96. A stop pin 97 (Fig. 9) assists in determining the vertical or operative position of the platen, while at the same time the bracket 93 may 60 65 be swung away from the stop about the axis

of the stud 95 when it is desired to inspect the ink rollers or to make other adjustments or repairs.

The plunger 92 has a roll 98 at its upper end engaging a cam 99 on a cam shaft 100 (Fig. 9). The shaft 100 is supported in bearings on the frame member 94 and is connected by a sprocket 101, chain 102 and sprocket 103 (Fig. 5) to the drive shaft 23.

The envelopes released by the conveyor belts 64 and 65 fall upon delivery belts 105 (Figs. 1 and 3) running over a collecting table 106. The belts 105 are mounted upon guide rolls 107 (Fig. 1) and driving pulleys 108 (Fig. 3) on a cross shaft 109. A ratchet wheel 110 (Fig. 2) is fixed on the shaft 109 and is intermittently actuated by a pawl 111 mounted on a swinging plate 112 which is connected by a link 113 to an eccentric stud 114 (Fig. 9) radially adjustable in a slotted disc 115 on the cam shaft 100. The rate of feed of the belts 105 may thus be varied by adjusting the stud 114 in the slotted disc 115.

The stencils S for use in the machine are 90 placed in the stencil magazine 116 (Fig. 9) from which the bottom stencil is successively removed by a transverse reciprocating feed plate or slide 117 (Fig. 10). This feed plate is provided with projections or ledges 118 for engaging and advancing the stencils and is connected by a link 119 to a lever 120 pivoted at 121 and connected by a link 122 to a counting device 123 (Fig. 9). A record is thus kept of the number of stencils removed from the stencil magazine 116.

The stencil slide 117 is actuated from an eccentric 124 on the cross shaft 37. The eccentric link 125 is provided with a give-way connection to a stud or pin 126 (Fig. 10) 105 on the lever 120. For this purpose, the head 127 of the link 125 is provided with an open notch in its upper surface to receive the pin 126 and a bell crank 128 is pivoted on the head 127 and is yieldingly forced against 110 the upper side of the pin 126 by a spring 129 carried by the link.

If a stencil becomes misplaced or the reciprocating movement of the slide 117 is otherwise prevented, the give-way connection permits the link 125 to be pulled off of the stud 126, thus preventing breakage of the feeding mechanism. When the link is disconnected from the lever 120, it is supported by a hook 130 (Fig. 9) provided 120 for this particular purpose.

Presser discs 131 (Figs. 1 and 3) are mounted upon rearwardly extending pivoted arms 132 and cause the envelopes discharged from the conveyor belts 64 and 65 to be more effectively engaged by the delivery belts 105.

Having thus described certain details of our improved addressing machine, the operation thereof will be readily apparent. A supply of envelopes is placed in the feed 130

box and a supply of stencils in the stencil magazine. The machine is then started and the envelopes are advanced one at a time to the conveyor belts 64 and 65 while at the same time the stencils are successively advanced by the stencil slide 117. As the envelopes are stopped by the pins 80, the presser foot 90 descends and the ink rollers at the same time engage the under side of the stencil, holding it against the superposed envelope. The presser foot rises, the stop pins 80 are withdrawn, the addressed envelope is advanced to the delivery belts 105 and a fresh stencil and envelope are simultaneously advanced.

After each stencil has been used, it is delivered to a collecting box or magazine 135 (Fig. 9) and is positively pressed downward therein by the foot 136 of a plunger 137 vertically slidable in a bearing 138 and connected by a link 139 to a crank pin 140 mounted on a disc at the end of the plunger shaft 100.

The sheet feeding mechanism herein described is not claimed in this application but forms the subject matter of a divisional application, Serial No. 740,442, filed by us September 29, 1924.

Having thus described our invention and the advantages thereof, we do not wish to be limited to the details herein disclosed otherwise than as set forth in the claims, but what we claim is:—

1. In an addressing machine, a plurality of stencils, a stencil slide by which said stencils are singly advanced in spaced re-

lation to addressing position, and means to reciprocate said slide at regular intervals, said means being positively actuated in both directions and including a connection 40 adapted to yield if feeding movement of said slide is obstructed.

2. In an envelope addressing machine, means to feed stencils positively in spaced relation, a counting device, driving means 45 for said feeding means and said counting device, and means to simultaneously disconnect said feeding means and said counting device from said driving means.

3. In an envelope addressing machine, 50 conveyor belts, delivery belts, continuous driving mechanism for said conveyor belts, adjustable intermittent feeding means for said delivery belts, and stop devices for positioning and releasing envelopes on said conveyor belts.

4. In an addressing machine, a frame, a platen, actuating means therefor, and a normally fixed support in which said platen is slidable, said support being pivotally secured to said frame and being movable manually about its pivot to swing said support and platen out of operative position in said machine, thereby permitting inspection of parts of the machine covered by 60 said platen.

In testimony whereof they have hereunto affixed their signatures.

EDWIN R. SMITH.
WILLIAM R. RICE.
JOHN R. JACKSON.
